UNITED STATES PATENT OFFICE.

NICHOLAS JOSEPH GONDOLF, OF NEW ORLEANS, LOUISIANA.

FLUSHING DEVICE.

1,259,226.

Specification of Letters Patent. Patented Mar. 12, 1918.

Application filed July 25, 1916. Serial No. 111,138.

To all whom it may concern:

Be it known that I, NICHOLAS J. GONDOLF, a citizen of the United States, and a resident of New Orleans, in the parish of Orleans 5 and State of Louisiana, have invented certain new and useful Improvements in Flushing Devices, of which the following is a specification.

My present invention relates principally 10 to a flushing device in which the float is depressed to start the siphon, and in practice, the features relating to the float and inlet valve are associated with a jet starter tube and with an after fill tube.

15 My invention relates particularly in novel means to actuate the float carrying structure and of other novel means associated with the first mentioned means to actuate the siphon starter jet and the after fill; also to 20 means to retain the float in depressed position and to prevent the float rebounding, the continued lowering of the float due to the emptying of the tank serving to release float from the retainer leaving the float free to 25 rise as the tank again fills.

In the drawings—

Figure 1 is a partial side view with parts broken away,

Fig. 2 is a top plan view,

30 Fig. 3 is a view similar to Fig. 1 showing the movable parts in normal position,

Fig. 4 is a section on line 4—4 of Fig. 3,

Fig. 5 is a detail section on line 5—5 of Fig. 2,

35 Fig. 6 is a detail section on line 6—6 of Fig. 5.

My invention is applicable to any conventional tank 10 of the "high tank" or "low tank" type though I have shown it in this 40 instance applied to a "low tank," this tank has the usual siphon 11 flared at the lower end and connected with the discharge 12 and an inlet pipe 13. A ball float 14 is adapted to be depressed for starting, 45 placing a portion of the water and a starting jet tube 15 adapted for entering the short leg of the siphon and to be moved out of the same, the tank receiving a supply of water from the inlet 13.

50 A rock shaft 16 is mounted in the tank and operated by a handle 16^a said shaft having a rock shaft member which consists of a pair of spaced apart arms 17, 17^a rigidly secured thereto at one end, the opposite ends converging and connected by a bolt 18 which is mounted to slide in slot 19 in the lever 20,

said slot gradually widening in its upper portion and terminating in a lateral curve or bend 21 being closed at this end so that the bolt cannot jump out of the slot and become 60 disconnected from the lever. The float rod 22 at one end is screwed into an internally threaded nipple 23 projecting from the lever 20 and at its opposite end to the float 14.

Water is supplied to the tank through the 65 inlet pipe 13 which has a contracted bore 13^a and the valve seat 13^b; this inlet pipe may be integral with or suitably secured to the valve casing in which works a piston or plunger inlet valve 25 which has a washer 70 25^a fitted in its lower end so as to tightly fit against the seat 13^b; the valve also has a split gasket 25^b fitted into an annular groove and the top is provided with an annular flange 25^c above the valve casing 24. The 75 casing is provided with a lateral pipe 26 in which is rotatably mounted the jet tube 15 which is provided with the annular collar 27 held adjacent the end of pipe 26 by the gland nut 28, which is in turn locked in place by 80 a set screw 29. The jet tube 15 has a curved end 15^a and the other end which is straight has a portion cut away equal to about one half its circumference as shown at 15^f in Fig. 6, the purpose of which will later appear. The pipe 26 has a lateral port 26^a to which a small pipe 30 is secured, said pipe extending upwardly and discharging into the siphon 11 as will be hereinafter more fully described, said pipe having a set screw 90 plug-valve 30^a to control same. The starting jet 15 has a weighted lug 15^b projecting from one side which is flexibly connected to one end of rod 32 which extending upwardly is connected to one arm 17^a by 95 means of a slot 17^b therein the upper end of rod 32 being secured by the bolt 33 passed through the slot 17^b from the inside through the rod and held by a lock nut 34, the head of the bolt being countersunk in the slot 17^b, 100 so that lever 20 will have unobstructed play between the two arms 17 and 17^a; the starting jet tube 15 also has a set screw plug valve 15^c to control the flow through the tube 30.

The valve casing 24 has the rigid bracket 105 arm 24^a on one side and a similar though shorter arm 24^b on the opposite side; the lever 20 has a bell crank arm 20^a which is pivoted to bracket arm 24^a and to the free end of 20^a is pivoted the lever 20^b flexibly 110 connected to lever 20^c which passes through the upper end of plunger 25 and is then

flexibly connected to the other bracket arm 24^b; this arrangement of levers is the means for connecting the float with the inlet valve 25.

5 As before stated the starting jet tub 15 is rotatably mounted in pipe 26 and the inner end extends into the lateral port of the valve casing, the cut-out portion uncovering the lateral port 26^a in pipe 26 when 10 rotated in one direction and the integral or blank portion covering said port when the jet starter is rotated in an opposite direction and these rotations are caused by the rod 32 connected at one end to the jet starter 15 by lug 15^c and at its opposite end to arm 17^a of the rocking means.

The lower end of the short leg of the siphon is flared sufficiently that when the jet starter tube is turned to one side its outlet will be entirely within the circumference of the flare.

20 With the parts in the position shown in Fig. 3 the tank being full, if it is desired to flush, the handle 16^a is depressed; this causes 25 the arms 17 and 17^a to move upwardly toward the right, the bolt 18 riding up the slot 19 of the lever 20 and finally rests in the extreme end of the curved slot 21 and locks the parts, the plunger valve 25 having 30 been raised by the movements of lever 20 and the starter jet tube being swung up to the position shown in Fig. 1 with its outer end projecting upwardly into the siphon leg; the jet starter having been swung or 35 rotated through the lug 15^b and the rod 32 the upper end of which is carried by the bolt which slides in the slot in arm 17^a; the jetting into the siphon causes the water to be rapidly discharged to the bowl and 40 this keeps up until water falls below the lower end of the short leg of siphon which breaks the siphonic action; the parts up to this point have been held in position by the water pressure on the float, but as 45 soon as water falls below the float it drops by its weight and this pulls lever 20 and causes the bolt 18 which connects the arms 17 and 17^a to fall back into slot 19, and this lowers arm 32 which is connected to lug 50 15^b on the starting tube 15 causing it, the lug, to swing downwardly and thus turn the starting tube through 90 degrees uncovering the port 26^a and permitting water to flow 55 through after fill pipe 30 to the upper part of the siphon; this action is caused by the plug valve 15^c which partially obstructs the bore 15 and causes back pressure through the port 26^a. As the tank refills the float rising swings lever 20 toward its normal position, the supply water feeding through 60 the jet tube 15 which as stated has been swung so that the curved end is turned out of the siphon leg. The after fill continues until the rising water through the float 65 forces the parts into position shown in Fig.

3 when the plunger valve 25 is held to its seat shutting off the inlet; the device is then again ready for use to flush.

The swinging movement of the jet starter 15 is aided by the weight of lug 15^b which 70 is connected to the rod 32, and to prevent the tube being entirely rotated and the lug 15^b being thrown over beyond center when the rod 32 pulls upwardly, a stop device is applied to the tube 15, which in its preferred 75 form consists of projecting boss or finger 15^d which will come in contact with bottom of the tank as indicated in Fig. 6; this it will be noted will prevent overthrow of the jet starter tube. The extra weight of the 80 lug is secured by the swell or enlargement 15^e.

I claim:

1. In a flushing apparatus the combination with a tank having a water supply 85 pipe and siphon discharge pipe therein, a valve casing connected to said supply pipe, and a valve therein, a jet starter tube communicating with the valve chamber, an after fill tube connected with said valve chamber 90 and means for rendering the after fill active when the starter jet becomes inactive.

2. In a flushing device, a float, an inlet valve operating lever, a rod carrying the float and connected at one end with said 95 lever, said lever having an elongated slot having a bent portion, a rock shaft mounted in the tank, a rocking member projecting from said shaft, and engaging the slot in said lever, whereby the float will be held 100 in a locked position during flushing, but permitted to rise and actuate the inlet valve during refilling operation.

3. In a flushing device of the character described a siphon, a fitting having an inlet, a lateral rotatable jet starter tube projecting from said fitting, an after-fill pipe connecting said inlet with the siphon, and means for simultaneously putting the starter jet into action and the after-fill out of action 105 upon the initial opening of the inlet.

4. In a flushing device of the character described a siphon and a float, a fitting having an inlet and a single outlet, a starter jet tube rotatably carried in said outlet, an after-fill connecting said inlet with the siphon, means carried by said jet tube controlling the said after-fill, and means actuated by the float and operably connected with the tube for putting the jet starter 115 into active position to discharge into the siphon.

5. The combination with a flushing tank including a siphon, of an inlet water valve, a casing therefor having a single outlet and 120 a port leading thereto, a jet starter tube rotatably carried in said outlet and adapted to discharge into said siphon, an after-fill tube connecting said port with the discharge leg of the siphon, a float and means 125

connecting said float with the inlet valve whereby opening of the inlet renders the jet starter tube active and the after-fill inactive.

5 6. The combination with a flushing tank of a siphon for discharging water therefrom, an inlet valve casing and valve therein, a lateral discharge pipe leading therefrom, a jet starter tube rotatably mounted
10 with respect to said lateral discharge, a supplemental port in said lateral discharge, an after fill tube leading from said port to the discharge leg of the siphon, a float, lever means operatively connecting said
15 float with the inlet valve, and means operated by the lever means to render the after-fill active, when the jet starter tube is rendered inactive.

7. In a flushing device a tank, a float and
20 a siphon, a valve casing and an inlet valve therein, a main operating lever operably connected to said valve and to the float, said lever carrying guide means, a rock shaft, a rocker arm carried by said rock
25 shaft, said rocker arm slidably engaging said guide means of the main lever, said guide means including an offset portion whereby to lock the rocker arm and main lever while the siphon is discharging.

30 8. In a flushing device of the character described a siphon discharge, an inlet valve casing, an inlet valve carried therein, a single outlet from said casing, and a bent inlet starter jet tube mounted to rotate with
35 respect to said port and discharge into the short leg of the siphon, and to be swung out of said leg, and means operably connecting the float and the inlet valve for causing rotary motion of the inlet starter
40 jet.

9. In a flushing device of the character described and including an inlet valve, siphon, float and rotatable inlet jet starter, and stop means carried by said starter for
45 limiting rotary movement thereof.

10. In a flushing device the combination of a tank, a siphon, an inlet valve, a float, and main lever connecting said float and valve, a valve casing carrying the inlet
50 valve, a rotatable inlet jet starter mounted to swing on said valve casing and communicating with the interior thereof, an after-fill tube connected with the interior of said

casing and discharging into the discharge of the siphon, a rock shaft, a rocker carried thereby and slidably engaging the main lever, said rocker including a slotted arm, a connecting rod slidably and pivotally mounted at one end in said slot and flexibly connected at its opposite end to the jet 60 starter tube, whereby the jet starter tube is swung into and out of the short leg of the siphon.

11. In a flushing device of the character described, the combination with a tank, of an inlet valve casing, a slideable plunger valve therein, a lateral outlet therefrom, a jet starter tube bent at one end and revolvably mounted at its opposite end with respect to the lateral outlet, a side port disposed in the side of said lateral outlet, the inner end of the jet starter tube controlling said port, an after-fill tube connecting said port with the discharge leg of the siphon, an inlet valve operating lever, a rock shaft, rocker 75 arms carried thereby and slidably engaging the valve lever, a float carried by the main valve lever, and means connecting the rocker arms, with jet starter tube, whereby said starter will be swung into the siphon, 80 and the after-fill shut off during such action, and after-fill tube opened when the jet starter tube is inactive as such.

12. A flushing device of the character described, including an inlet valve-chamber 85 and valve therein, a movable jet-starter communicating with said chamber, an after-fill tube also communicating with said valve chamber, and means carried by said jet-starter for causing back pressure within 90 the jet-starter intermediate its outlet and the inlet to the after-fill when said jet-starter is moved to inactive jetting position.

13. A flushing device of the character de- 95 scribed including an inlet valve chamber and valve therein, a movable jet starter communicating with the valve chamber, an after-fill tube also communicating with said valve chamber, and means carried by said 100 jet starter for preventing flow through the after-fill to the discharge of the siphon, when said jet starter is moved to active jetting position.

NICHOLAS JOSEPH GONDOLF.
